INVENTOR:

Frederick Lobl,

By Emery Booth, Jameson & Varney,
Attest,

UNITED STATES PATENT OFFICE.

FREDERICK LOBL, OF BOSTON, MASSACHUSETTS.

CONTAINER.

1,269,103.

Specification of Letters Patent. Patented June 11, 1918.

Application filed December 9, 1916. Serial No. 136,060.

To all whom it may concern:

Be it known that I, FREDERICK LOBL, a subject of the Emperor of Austria, and a resident of Boston, county of Suffolk, and 5 State of Massachusetts, have invented an Improvement in Containers, of which the following description, in connection with the accompanying drawings, is a specification, like characters on the drawings representing 10 like parts.

This invention relates to containers and particularly to articles of this nature having a large body and a relatively smaller neck or filling opening such as the ice and hot 15 water bags common in use, and aims to provide an improved article of this description.

The embodiment of my invention illustrated and described in this application is an ice bag, and

In the drawings:

Figure 1 is a side elevation;

Fig. 2, a vertical section on the line 2—2 Fig. 1, of an ice bag embodying my invention, and

Fig. 3 is a lower face view on a smaller scale of the stopper.

The bag 1 may be of any flexible and suitable material as rubber, or water-proof cloth, and of convenient size and shape. The bag is commonly made from a circular piece of material and in order that it may have reasonably large capacity with a convenient opening, it is common to fold or plait the sides of the bag vertically by hand, thereby permitting its expansion as desired and permitting also, the upper end or edge to be gathered so to speak, sufficiently to fit the neck member at the opening.

In the drawing, the bag is shown as 10 formed with a plurality of successive longitudinal folds 2, which at the top are laid on a suitable neck member 3. These folds are preferably made wider at the lower end of the bag than at its upper end so that when the bag is expanded, after the contents are placed therein, the folds will permit of a substantial expansion in the width of the bag and still have it conform substantially to the shape of the bag at its upper or top end, producing a bag when partially filled, substantially tubular or cylindrical in shape. This shape of bag has been found to be the most practical and convenient for use in cases where such bags are commonly required.

Heretofore it has been the practice to se-

cure the folded material 1 to the neck 3 by means of wires or cords wound about the bag 1 and neck member, and suitably fastened. These wires are then covered by a 60 narrow strip of suitable material as that of which the bag is made in any convenient manner, as by cementing the same to the neck 3 over the wires.

This method is expensive and unsatisfactory in that the covered wires are always noticeable to some extent, and are apt to become rusty. This method further does not always make a tight joint; and the narrow strip frequently becomes loose and pulls off. 70

I have conceived the novel idea of securing the bag to the neck by compressing the bag tightly against the same by means of a suitable band or flange. One satisfactory method Fig. 2, is to provide the metallic 75 neck 3, which is threaded on its inner wall 4 to receive the usual stopper, with a relatively wide laterally extended flange 5, normally extended therefrom, see dotted lines Fig. 2.

In assembling, the bag edge or end 6 is positioned adjacent the angle 7 of the neck member and the flange 5 is then, by any convenient means, bent downwardly and compressed tightly against the bag, effectually locking it between the neck 3 and its flange 5. If desired, rubber or other cement may be applied to that part of the bag to be covered by the flange and also to the surface of the neck 3, for more thoroughly guarding 90 against leakage.

The neck, when secured to the bag in the manner described, is securely locked thereto and furthermore it presents an attractive appearance.

If desired, the flange 5 may be perforated as at 8, Fig. 2, so that when the flange 5 is compressed against the bag the latter will be forced up into the perforations 8 and thus provide a plurality of anchorages in 100 connection with the neck 3 which add to the security of the joint.

I have also conceived a novel form of stopper for the bag wherein the usual washer may be locked thereto so that it will 105 not drop off. Frequently after a washer has been used for a time it will become more or less hardened and stretched, and drop off easily.

To avoid this annoyance, I have formed 110 the stopper 9 of two pieces, the body 10 being threaded to engage the neck 3 as usual,

The upper edge 11 of the body is extended laterally and forms a seat for the washer 12. The top of the body 9 is, in this case, substantially a disk, convex if desired, and having its edge turned inwardly and upwardly against the edge of the washer 10 to securely hold it in position. If preferred, Fig. 3, instead of turning the entire disk edge inwardly and upwardly, the disk may 10 be of such size as to register with the lower face of the edge of the flange and the disk edge provided with tabs 13 in sufficient number which may be readily turned up against the washer to hold it in place, and 15 the disk is so shown in this case. This permits the ready replacing of the washer by a new one when desired, as the tabs can readily be manipulated by hand.

Doubtless modifications of the foregoing 20 embodiment of my invention may be made

within the scope of the appended claim and the spirit of the invention as disclosed.

Claim:

An expandible receptacle comprising a sheet of flexible material folded to form a neck portion, a threaded neck band within and adjacent the neck portion to receive interiorly a threaded stopper, said threads also constituting a roughened outer surface to grip the neck portion of the flexible receptacle, said neck band having an outwardly and downwardly turned perforated flange compressed against said neck portion, the latter being forced outward by the compressing action into the perforations to lock the neck band and neck portion of the receptacle together. 25 30 35

In testimony whereof, I have signed my name to this specification.

FREDERICK LOBL.
